CLAIM

The ornamental design for a container for food, as shown and described.

DESCRIPTION

FIG. 1 is a top perspective view of a container for food showing our new design;

FIG. 2 is a bottom perspective view thereof;

FIG. 3 is a front view thereof;

FIG. 4 is a back view thereof;

FIG. 5 is a right side view thereof;

FIG. 6 is a left side view thereof;

FIG. 7 is a top view thereof;

FIG. 8 is a bottom view thereof;

FIG. 9 is a top perspective view of the top portion of the design thereof;

FIG. 10 is a bottom perspective view of the top portion of the design thereof;

FIG. 11 is a front view of the top portion of the design thereof;
FIG. 12 is a back view of the top portion of the design thereof;
FIG. 13 is a right side view of the top portion of the design thereof;

FIG. 14 is a left side view of the top portion of the design thereof;

FIG. 15 is a top view of the top portion of the design thereof;

FIG. 16 is a bottom view of the top portion of the design thereof;

FIG. 17 is a top perspective view of the bottom portion of the design thereof;

FIG. 18 is a bottom perspective view of the bottom portion of the design thereof;

FIG. 19 is a front view of the bottom portion of the design thereof;

FIG. 20 is a back view of the bottom portion of the design thereof;

FIG. 21 is a right side view of the bottom portion of the design thereof;

FIG. 22 is a left side view of the bottom portion of the design thereof;

FIG. 23 is a top view of the bottom portion of the design thereof; and,

FIG. 24 is a bottom view of the bottom portion of the design thereof.
